(57) **CLAIM**

The ornamental design for a skate with remote controller as shown and described.

DESCRIPTION

FIG. 1 is a front view of a skate with a remote controller according to our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a bottom front perspective view thereof;

FIG. 8 is an enlarged view of a portion labeled with “8” of the bottom front perspective view in FIG. 7;

FIG. 9 is a front perspective view thereof;

FIG. 10 is a rear perspective view thereof;

FIG. 11 is a front view of the remote controller of the skate;

FIG. 12 is a right side view thereof;

FIG. 13 is rear view thereof;

FIG. 14 is a left side view thereof;

FIG. 15 is a top view thereof;

FIG. 16 is a bottom view thereof;

FIG. 17 is a front perspective view thereof; and,

FIG. 18 is a rear perspective view thereof.

Portions shown in dot-dot-dash broken lines define the bounds of the claimed design and form no part of the claimed design. Portions shown in dashed broken lines are for the purpose of illustrating and form no part of the claimed design.

1 Claim, 14 Drawing Sheets
